(57) **CLAIM**

The ornamental design for an ionizer, as shown and described.

DESCRIPTION

FIG. 1 is a front, top, and left side perspective view of an ionizer showing the new design.

FIG. 2 is a rear, bottom, and right side perspective view thereof.

FIG. 3 is a front elevational view thereof.

FIG. 4 is a rear elevational view thereof.

FIG. 5 is a top plan view thereof.

FIG. 6 is a bottom plan view thereof.

FIG. 7 is a left side elevational view thereof.

FIG. 8 is a right side elevational view thereof.

FIG. 9 is an enlarged view of the portion labeled 9 in FIG. 3.

FIG. 10 is an enlarged view of the portion labeled 10 in FIG. 6; and,

FIG. 11 is an enlarged view of the portion labeled 11 in FIG. 2.

The evenly spaced broken lines shown in the figures are for the purpose of illustrating portions of the ionizer that form no part of the claimed design. The dot-dash broken lines shown in the figures on the ionizer illustrate a boundary of the claimed design that forms no part of the claimed design.

1 Claim, 10 Drawing Sheets
